UNITED STATES PATENT OFFICE.

DANIEL HEPP, OF CHICAGO, ILLINOIS.

BORING-MACHINE.

SPECIFICATION forming part of Letters Patent No. 761,171, dated May 31, 1904.

Application filed May 21, 1903. Serial No. 158,187. (No model.)

To all whom it may concern:

Be it known that I, DANIEL HEPP, a citizen of the United States, residing at Chicago, in the county of Cook and State of Illinois, have 5 invented certain new and useful Improvements in Boring-Machines; and I do declare the following to be a full, clear, and exact description of the invention, such as will enable others skilled in the art to which it appertains to make and use the same.

This invention relates to boring-machines, and more particularly to machines for boring the rails and stiles of doors, window-shutters, and other woodwork.

15 The object of the invention is to provide a machine of this character by means of which the rails and stiles may be rapidly and perfectly bored without being marked or laid out, so that when put together the doors or 20 frames will be absolutely square and have perfectly-true faces.

Further objects are to produce a machine of this character which is simple and durable in construction and very efficient in operation.

25 With these and other objects in view the invention consists of certain novel features of construction, combination, and arrangement of parts, as will be more fully described, and particularly pointed out in the appended 30 claims.

In the drawings, Figure 1 is a top plan view of a machine embodying my invention. Fig. 2 is a side elevation of the same. Fig. 3 is an end elevation of the machine. Fig. 4 is a vertical longitudinal sectional view taken on the plane indicated by the line $x-x$ of Fig. 5. Fig. 5 is a vertical transverse sectional view taken on the line $5-5$ of Fig. 1. Fig. 6 is a detail view showing the manner of clamping 40 the work upon the work-holders. Fig. 7 is a detail view showing the locking-plate for the drive-shaft. Fig. 8 is a detail longitudinal sectional view through one of the double tool-holders or boring-heads, taken on the plane indicated by the line $y-y$ of Fig. 9. Fig. 9 is 45 an end elevation of the same.

Referring to the drawings more particularly, the numeral 1 denotes the main frame of the machine, upon which a boring-head-supporting frame 2 is adjustably mounted. The

frame 2, upon which a series of double or compound tool-holders or boring-heads 3 are adjustably secured, is adapted to be adjusted vertically by providing upon the under side of the same the inclined portions or blocks 4, 55 which engage the similarly-inclined portions 5 upon a lower box or frame 6. The box 6 is mounted in the main frame 1 so as to slide longitudinally and is adjusted by providing the screw 7, which passes through a threaded 60 aperture in one end of the main frame and has its inner end swiveled to said box or frame 6. The outer end of said screw is provided with a hand-wheel 8, by means of which it may be operated to move the sliding lower 65 frame 6 longitudinally. Since the upper supporting-frame 2 is supported in the frame 1 by the inclined portion 4, resting upon the inclined portion 5, it will be seen upon reference to Fig. 4 of the drawings that the longitudinal or horizontal movement of the lower frame will impart a vertical movement to the upper frame 2. The purpose of this adjustment will be hereinafter explained.

Each of the boring-heads 3, of which any 75 number may be employed, comprises the transversely-disposed plate or frame 9, upon which the bits and driving-gear for the same are mounted. These bit-frames 9 have a dovetail connection with the supporting-frame 2, 80 as shown at 10, in order to permit them to be moved longitudinally thereon and are adapted to be held in an adjusted position by the clamping-screws 11.

Upon the top of the bit-frames 9 suitable 85 boxes 12 are provided, in which the spindles of the bits and other gearing are journaled.

13 denotes the bits, one of which is secured in each end of the spindles 14, which are journaled in the boxes 12. Any desired number 90 or arrangement of these spindles may be used, and the shanks of the bits are removably secured in the same by being inserted in the bore in each end of the spindle and by being clamped by screwing the nuts 15 upon the 95 split tapered ends of the spindles.

Each of the spindles 14 is provided with a gear 15', which meshes with the gears 16 upon the short shafts or spindles 17. The spindles 17 are arranged above and between the spin- 100

dles 14, so that each of the gears 16 will mesh with two of the gears 15. One of the gears 16 is in mesh with a larger drive-gear 18, keyed to a shaft or spindle 19, upon which a 5 drive-pulley 20 is also secured. An idler-pulley 21 is disposed above said pulley or driver 20 and is secured to a shaft or spindle 22. While all of these spindles may be journaled in any desired manner, I preferably provide 10 the removable bushings or tubes and journal the spindles therein, as illustrated in Fig. 8 of the drawings.

In order to rotate the bits by means of the gearing just described, a belt 23 is passed 15 about the pulleys 20 and 21, as shown in Figs. 2 and 4 of the drawings. This belt also passes under the guide or idler pulleys 24 at each 20 end of the machine. The pulleys 24 are each secured to a shaft or spindle 25, which is suitably journaled in bearing-boxes upon a frame 26, secured at each end of the machine to the supporting-frame 2. The belt 23 passes up over a pulley (not illustrated) upon an-overhead power-shaft, by means of which it may 25 be driven.

Disposed upon each side of the main frame is a movable work-holder 27, which is adapted to be moved toward and from said frame and the boring-heads mounted thereon. These 30 work holders or benches 27 are secured to the reciprocating or sliding bars 28, which project through the bearings 29, formed in the main frame 1, and through bearings 30, formed in the supports or standards 31, which are disposed at each side of the main frame.

The work holders or benches 27 are adjustably secured to the sliding rods, and each comprises the channel-iron bench or table 32, to the under side of which the clamping-brackets 33 are bolted or otherwise secured. The split ends 34 of the brackets, through which the rod 28 passes, are clamped upon the same by the screws 35. Adjustably mounted upon the top of the benches or tables 32 are the sliding plates 45 or guides 36, which are adapted to be clamped upon the benches by means of a clamping-bolt 37 and nut 38. This bolt 37 passes through the downwardly-projecting inner portion 39 of the guide 36 and through a longitudinal 50 slot formed by the bottom of the inner side of the bench 36 and an angle-iron strip 40, which is secured upon the brackets 33 below the said bench. The head of this bolt 37 is upon the inner side of the slot thus formed, and the clamping-nut 38 is screwed on the threaded end of the bolt upon the outer face of the portion 39. It will be observed that by this construction the guides 36 may be adjusted at any desired points on the bench 32. 55 The top of the guides are provided with the fixed stop 41 and the apertures 42, in which the stop-pins 43 are inserted, as hereinafter described.

As shown in Figs. 1 and 5 of the drawings, 60 the stile S or the rail R rests upon the guides

36, and in order to support the rail R in a horizontal position I provide the supporting-rods 44, which are carried by the adjustable brackets 45. These brackets have their lower ends clamped upon the outer ends of the sliding bars 28 by the screws or bolts 46, and their upper ends are bored and cut away, as shown at 47, in order to receive the supporting-rod 44. When it is not necessary to use this rod 44, it may be pulled out of the brackets by 75 sliding the same longitudinally, and the brackets may also be removed. Adjustable stops in the form of blocks 48 are secured upon the supporting-rods by suitable set-screws and are adapted to assist in holding the rails R at 80 right angles to the machine. In order to hold the work, either the stile or the rail, upon the guides during the boring operation, the same is clamped down by means of a beam or bar 49. (Shown in Fig. 6 of the drawings.) 85 These beams, which extend longitudinally over the benches or tables 32, have their ends clamped under the clamping brackets or arms 50, which are formed at each end of the benches. A pressure head or nut 51, swiveled upon the 90 end of a screw 52, which passes through the bracket, is adapted to bear upon the beam 49 to clamp the same. The screw 52 is provided at its upper end with an operating hand-wheel 53.

As previously stated, the work holders or benches are secured to the sliding bars 28, which when reciprocated will bring the work clamped upon the two benches alternately up to the compound or double-end boring-heads 3. 100 As illustrated in the drawings, the reciprocating movement of these rods may be imparted from the drive-shaft 54 in either of two ways. This drive-shaft 54 extends longitudinally through the center of the machine between the sides of the main frame and is journaled in suitable bearings in the ends of said frame.

55 denotes gears or pinions secured to the drive-shaft at intervals corresponding to the 110 spaces between the sliding bars and adapted to mesh with the rack-plates 56, which are clamped upon the sliding bars. 57 denotes grooved cam-plates secured upon the said shaft at corresponding intervals, and 58 denotes brackets clamped to the sliding bars and carrying the studs or projections 59, which are adapted to travel in the cam-grooves of the plates 57. The drive-shaft 54 has a slight longitudinal or sliding movement to permit 120 either the pinions and racks or the cam-plates and studs to be moved into and out of engagement with each other.

It will be understood that when the pinions 55 and the racks 56 are in mesh the studs 59 125 will not project into the cam-grooves in the plates 57. The rotation of the drive-shaft when the studs 59 engage the cam-plates 57 and the pinions and racks are not in mesh will cause the sliding rods 28 to be reciprocated 130

back and forth a predetermined distance, owing to the travel of the studs in the cam-grooves. When the cam-plates operate the sliding rods, it will be seen that the reciprocation or movement of the benches toward the boring-heads 3 will always be definite and the same, so that this cam-gearing is used when regular work is done upon the machine—that is, when all the holes bored are to be the same depth. When it is desired to bore any special work or when it is desired to bore the holes to a greater or less depth than they would be bored by using the cam feed or gearing, I disengage the latter and throw the racks 55 and pinions 56 into gear by shifting the shaft lengthwise. When this rack-gearing is employed, the drive-shaft must be rotated alternately in reverse directions, and this I accomplish by means of frictional gearing, hereinafter described.

The shaft is adapted to be locked against sliding or longitudinal movement by providing adjacent to one end the annular grooves 60, one of which is adapted to be engaged by the semicircularly-notched plate 61, which is clamped upon one end of the machine by the clamping-bolt 62 passing through an elongated aperture or slot in the plate to permit adjustment of the same. Each end of the 25 drive-shaft 54 is provided with a hand-wheel 63, by means of which it may be adjusted and turned.

Fixed upon the drive-shaft adjacent to one end is a large friction-gear 64, which is adapted to be engaged and driven by either one of the two small friction-wheels 65. These wheels 65 are carried by an operating or shifting lever 66, which is adapted to hold either of the wheels 65 in contact with the large friction-wheel 64. The lever 66 has its lower end pivoted at 67 to one end of the main frame and is formed with the central opening 68, through which the shaft 54 projects. The small friction-rollers 65 are secured upon 35 shafts 69, which are journaled in the bearing-brackets 70 upon each side of the lever. The upper end of the lever is formed with an operating-handle 71 and with the three notches or apertures 72, through which and an aperture in the end of the main frame a pin or bolt 73 may be passed to hold the lever in any desired position. When the lever is in its central position, as shown in Fig. 3 of the drawings, both of the small friction-wheels are out of contact with the large friction-wheel, and when the lever is moved to either side and locked by the pin 73 one or the other of the small wheels will be held against the large one. Upon the shafts or spindles 69 are also secured 50 the pulleys 74, which are adapted to be connected by the belts 75 to suitable pulleys (not illustrated) upon an overhead power-shaft. One of the belts 75 is crossed in order to drive one of the pulleys 65 in the reverse direction 60 from the other of said pulleys. It is thus

seen that the drive-shaft 54 will be rotated in either direction, as desired, according to which of the two wheels 65 engages the large wheel 64.

The operation of the machine is as follows: 70 When it is desired to bore rails, they are placed upon the guides 36 and rods 44 and clamped down against the stops 41, 42, and 48 by the beams 49, as previously explained. When stiles are to be bored, they are placed longitudinally upon the guides 36 and clamped in a similar manner. The machine is designed to be controlled by two operators, one being upon each side. After the bits are set in motion by means of the gearing previously described, which is driven by the belt 23, the lever 66 is shifted to either side to bring one of the small friction-wheels into engagement with the large friction-wheel 64 upon the drive-shaft 54 in order to rotate the latter. 80 When the drive-shaft is connected with the sliding bars 28 by the cam-gearing, it will be seen that the work-holders upon each side of the machine will be moved alternately toward and from the boring-heads in order to bore 90 the holes in the work upon said benches, as will be readily understood. By moving the lever 66 to its central position the movement of these work-holders will be stopped. When the rack-and-pinion gearing connects the 95 sliding bars and the drive-shaft, it will be necessary to throw the lever 66 first to one side and then to the other in order to permit one of the reversely-driven friction-wheels 65 to move the shaft in one direction and then to permit 100 the other small wheel 65 to reverse the movement of the shaft. By means of this gearing it will be noticed that the work-holders may be moved any desired distance toward or from the boring-heads, and hence the holes may be 105 bored to any desired depth.

By operating the hand-wheel 8 it will be seen that the supporting-frame for the boring-heads may be raised or lowered, and thus permit the bits to be adjusted vertically to accommodate lumber of different thicknesses. Owing to the sliding connection of the boring-head frames 3 with the frame 2, the said heads may be adjusted horizontally. By making the benches 32, guides 36, supports 44, and 110 the various parts adjustable, as previously explained, it will be seen that various kinds of woodwork may be bored upon the machine. By providing the cam and the gear feeds for the work-holders or benches the regular depth 115 of boring or a greater or less depth than the regular may be had.

From the foregoing description, taken in connection with the accompanying drawings, the construction and operation of the invention will be readily understood without requiring a more extended explanation.

While I have shown and described my invention in its preferred form, it will be understood that various changes in the form, 125

proportion, and the minor details of construction may be resorted to without departing from the principle or sacrificing any of the advantages of this invention.

5 Having thus fully described my invention, what I claim, and desire to secure by Letters Patent, is—

1. The combination with a boring-head and a work-holder, one shiftable toward and from the other, a shaft, means to rotate the shaft, and interchangeably effective means, operated by the shaft to shift one of the first-mentioned elements, one of said shifting means being effective to shift said shiftable element to an invariable extent, and the other of said shifting means being effective to shift said shiftable element to a variable extent, substantially as described.
2. In a boring-machine, the combination of a suitable main frame, double tool-holders or boring-heads mounted thereon, sliding bars in said main frame, work-holders upon said sliding bars at each side of the main frame, a drive-shaft in said main frame, and an interchangeable rack-and-pinion or cam gearing between said shaft and sliding bars, substantially as described.
3. In a boring-machine, the combination of a suitable main frame, double tool-holders or boring-heads mounted thereon, sliding bars in said main frame, work-holders upon said sliding bars at each side of the main frame, a

drive-shaft in said main frame, a rack-and-pinion gearing between said shaft and sliding bars, and a cam-gearing between said shaft and sliding bars, said shaft being slidable to throw either said cam or said rack-and-pinion gearing into or out of operation, substantially as described.

4. In a boring-machine, the combination of a suitable main frame, an adjustable supporting-frame mounted thereon, double tool-holders adjustably mounted upon said supporting-frame, sliding bars in said main frame, adjustable work-holders upon said sliding bars at each side of said main frame, a drive-shaft in said main frame, and an interchangeable cam or rack-and-pinion gearing between said shaft and sliding bars, substantially as described.

5. In a boring-machine, a reciprocating work-holder comprising sliding bars, adjustable benches or tables upon said sliding bars, adjustable guides or plates upon said benches, and adjustable supporting-rods upon said sliding bars, substantially as described.

In testimony whereof I have hereunto set my hand in presence of two subscribing witnesses.

DANIEL HEPP.
